UNITED STATES PATENT OFFICE.

MARCELIN DAIGLE, OF HOUMA, LOUISIANA.

BRIDGE.

SPECIFICATION forming part of Letters Patent No. 332,058, dated December 8, 1885.

Application filed October 3, 1885. Serial No. 178,907. (No model.)

To all whom it may concern:

Be it known that I, MARCELIN DAIGLE, a citizen of the United States, and a resident of Houma, in the parish of Terrebonne and State of Louisiana, have invented certain new and useful Improvements in Bridges; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a side view of my improved 15 draw-bridge, showing it spanning the stream. Fig. 2 is a longitudinal vertical sectional view of the same, showing the bridge drawn back; and Fig. 3 is a plan view of the bed and carriage of the bridge, the bridge proper being 20 removed.

Similar letters of reference indicate corresponding parts in all the figures.

My invention has relation to that class 25 of draw-bridges in which the bridge proper travels on rollers and spans the river or stream across which it is drawn with one-half of its length; and it consists in the improved construction and combination of parts of the same, as hereinafter more fully described and 30 claimed.

In the accompanying drawings, the letter A indicates the abutment, upon which the outer end of the draw B rests when spanning the stream, and C indicates the base upon which 35 the bridge travels, and which is either upon the bank or the portion of the bridge nearest to the bank. The base is provided with two longitudinal rails, D D, usually consisting of two parallel beams, faced upon their upper 40 sides with iron. The carriage E travels upon the track formed by these rails, and consists of a frame, F, having one shaft, G, journaled transversely in its inner end, provided with two rollers or flanged wheels, H H, which travel 45 upon the track, and two transverse shafts, I I, journaled at its outer end, provided with flanged wheels or rollers J J and K K, which likewise travel upon the track. The transverse shafts at the outer end of the carriage 50 are provided with cog-wheels L L, which mesh with a pinion, M, upon a shaft, N, jour-

naled transversely in the forward end of the frame, and the outer end of this shaft is provided with a cog-wheel, O, which meshes with a pinion, P, upon a short shaft, Q, provided with a crank, R, for revolving it, the said outer end of the shaft N and the short shaft provided with the crank being journaled in a frame, S, secured upon a platform, T, at one side of the outer end of the carriage. 55 60

The draw has two parallel longitudinal rails or beams, U U, faced upon their lower sides with iron, and these beams or rails travel upon the upper sides of the flanged rollers of the carriage, the said rollers projecting with their 65 edges above and below the frame.

The draw is preferably of the usual truss form, having upright posts V V at its middle, and braces W W secured at the ends of the bridge and passing over the upper ends of the 70 upright posts, and provided with the usual tightening-links, X. It will now be seen that when the crank is turned from left to right, or with the sun, the rollers will travel out upon the track upon the base, and at the same time act 75 upon the rails of the draw, forcing them outward, closing the draw, while when the crank is turned in the opposite direction, against the sun, the carriage will travel inward and the draw will likewise travel inward. 80 8c

By reason of the carriage being interposed between the draw and the base-rails, the track for the carriage needs not to be as long as if the draw was provided with rollers and traveled upon the track, the track being only the length 85 of the carriage and one-half of the distance from the base to the abutment, while if the carriage was dispensed with and the draw provided with the rollers traveling upon the base-rails, the said rails would have to be the length 90 of the entire draw. Time is also saved by interposing the carriage, inasmuch as the draw does not only travel with the speed with which its rails travel upon the rollers, but to this speed is added the speed with which the 95 carriage travels upon the base-rails, so that the bridge is moved in or out with double the speed with which it would move if it traveled directly upon the base-rails.

The inner end of the draw may either be inclined upon its upper side, so as to make an 100 easy ascent from the road-bed to the draw, or

it may be provided with a hinged flap, Y, having chains Z Z secured at its outer end and passing over pulleys A' upon the tops of posts B' at the end of the draw, the said chains being provided at their inner ends with eyes C'.
5

Shaft N is provided near its ends with drums D', formed with hooks E' upon their faces, and the eyes of the chains may be secured upon these hooks for the purpose of winding the 10 chains upon the drums when it is desired to raise the flap or for lowering it.

For the purpose of allowing the shaft N to revolve without revolving the pinion upon the same, the said pinion turns upon the shaft, and 15 is provided with a half-clutch, G', upon one face, which engages a half-clutch, H', which slides upon the shaft and turns with it. The latter half clutch is formed with a peripheral groove, I', into which the bifurcated ends J' of 20 an elbow-lever, K', fit, and the clutch may be thrown into or out of engagement with the clutch upon the pinion by means of this elbow-lever.

The hoisting-chains for the flap are provided 25 with additional chains, L' L', which may be hooked upon pins M' upon the sides of the draw, so that the flap may be held raised while the carriage and draw are moved, the eyes of the hoisting-chains being removed from the 30 hooks upon the drums.

Having thus described my invention, I claim and desire to secure by Letters Patent of the United States—

1. In a draw-bridge, the combination of a 35 base provided with parallel track-rails, a carriage having flanged rollers or wheels traveling upon the said rails, a draw having parallel rails traveling upon the rollers, and means for revolving the rollers, as and for the purpose 40 shown and set forth.

2. In a draw-bridge, the combination of a base provided with parallel track-rails, a carriage provided with transverse bearings in its outer and inner ends, a shaft journaled in the

inner bearings, and provided with flanged rollers or wheels traveling upon the base-rails, two shafts journaled in the forward bearings, and provided each with a cog-wheel at their middles and with flanged rollers or wheels traveling upon the track, a shaft provided with 45 a pinion meshing with the cog-wheels and having means for revolving it, and a draw traveling with parallel rails upon the rollers or wheels, as and for the purpose shown and set forth.
50

3. In combination with a base provided with parallel rails, a draw provided with corresponding parallel rails, and carriage having transverse shafts at its ends, provided with rollers traveling upon the base-rails and having the draw-rails traveling upon them, the shafts of the two pairs of front rollers being provided with cog-wheels, of a flap hinged to the rear end of the draw, and having chains secured to its outer ends and passing over pulleys upon posts at the rear end of the draw, and formed with eyes at their inner ends, a shaft journaled transversely in the front end of the carriage, and provided with a pinion turning upon it and meshing with the cog-wheels upon the forward transverse shafts, and provided with drums at its ends having hooks for the reception of the eyes of the chains, means for revolving the said shaft, a clutch turning with and sliding upon the shaft 65 and engaging a clutch upon the pinion upon the shaft, means for sliding the said pinion, and means for supporting the flap when the chains are removed from the drums, as and for the purpose shown and set forth.
70

In testimony that I claim the foregoing as my own I have hereunto affixed my signature in presence of two witnesses.

MARCELIN DAIGLE.
